[57] CLAIM

The ornamental design for a video display and catalog system, as shown and described.

DESCRIPTION

FIG. 1 is a front right-hand elevational perspective view showing the video display and catalog system of our new design;

FIG. 2 is a left side view thereof;

FIG. 3 is a front view thereof;

FIG. 4 is a top view thereof;

FIG. 5 is a front right-hand elevational perspective view of the video display and catalog system of FIG. 1, with the interactive display component of our new design shown in isolation;

FIG. 6 is a side view of the design shown in FIG. 5;

FIG. 7 is a front view of the design shown in FIG. 5;

FIG. 8 is a top view of the design shown in FIG. 5;

FIG. 9 is a front right-hand elevational perspective view of the outer housing of the video display and catalog system of FIG. 1, with the interactive display removed therefrom; and, FIG. 10 is a left-side view of the design of FIG. 9, the right-side view thereof being a mirror image thereof.
